UNITED STATES PATENT OFFICE.

OTTO P. WATSON, OF MICHIGAN CITY, INDIANA, ASSIGNOR TO RELIANCE MANUFACTURING COMPANY, OF CHICAGO, ILLINOIS, A CORPORATION OF INDIANA.

SEWING MACHINE.

Application filed December 6, 1922. Serial No. 605,142.

My invention relates to improvements in sewing machines, and is particularly concerned with improvements in sewing machines embodying a double needle bar.

Considerable difficulty has heretofore been experienced with sewing machines of this type because of the frequent breakage of the one needle bar at the point where one or more screws pass through it. Another objection to the type of double needle bar machine heretofore employed is that it is necessary to stop the sewing machine before a corner can be turned in the goods which is being operated upon.

The principal objects of my invention are to provide a sewing machine of the double needle bar type which will overcome the defects in the types of machines heretofore used, by providing a machine in which the metal of the two needle bars is so disposed as to insure a maximum degree of strength and which do not require the passage of screws or other similar devices to secure them to adjacent parts.

Another object of my invention is to provide a sewing machine of the character described which need not be stopped when it is desired to turn a corner.

A still further object of my invention is to provide a sewing machine of the character described which is simple in construction, economical to manufacture and easy to operate.

Other objects will appear as this description progresses, reference being had to the accompanying drawings, in which

Figure 1 is a side elevation showing a portion of the head of a sewing machine embodying one form of my invention;

Figure 2 is a plan thereof;

Figure 3 is a vertical longitudinal section taken on line 3—3 of Figure 2;

Figure 4 is an end view;

Figure 5 is a view similar to Figure 4 except that certain of the parts have been broken away for the purpose of better illustration;

Figure 6 is a view similar to Figure 5, but showing certain of the parts in a different relation;

Figure 7 is a sectional detail; and

Figure 8 is a transverse section taken on line 8—8 of Figure 3.

Throughout the views similar reference characters will be used for referring to simi-

lar parts, and the sections are taken looking in the direction of the small arrows.

In the embodiment of my invention illustrated in the drawings, I have illustrated a sewing machine comprising a hollow head 10, which is so shaped as to receive the mechanism about to be described. The upper and lower sides of this head are provided with the aligned upper and lower bearings 11 and 12, respectively, the lower one being of greater diameter than the upper one. A hollow or tubular needle bar 13 is slidably mounted in the bearing 12 and a second needle bar 14, preferably formed of solid round stock, is slidably mounted in the hollow needle bar and the upper bearing 11. A boss 15 projects outwardly from the upper end of the hollow needle bar 13 and reciprocates in a slot 16 formed in the face plate 17 which is secured to the end of the head, thereby preventing rotation of the needle bar 13. This boss also projects through the slot 18 formed in the link 19.

A shaft 20, which is mounted in the arm 21 of the sewing machine, projects into the head 10 and is provided with a crank arm 22 carrying the eccentric pin 23. A pitman rod 24 connects the eccentric pin 23 with the wrist pin 25 on the lower end of the bar 26, which partially embraces the needle bar 14. The upper end of the bar 26 is rigidly secured to the needle bar 14 by means of the clamping block 27 (see Figures 3 and 7) and the screws 28, which extend through the clamping block 27 and into a projecting flange on the upper end of the bar 26. A boss or pin 29 projects outwardly from the clamping block 27 and extends through an opening in the upper end of the link 19. A latch 30 is pivotally mounted upon the boss 15 and its upper end is cut away, as shown at 31 (see Figure 6), so that when the latch 30 is moved to the position shown in Figure 5, the latch will engage beneath the pin or boss 29, thus locking the two needle bars together. When, however, the latch 30 is moved to the position shown in Figure 6, the needle bar 14 will be free to reciprocate, but the hollow needle bar 13 will not be locked to it and will not, therefore, reciprocate with the needle bar 14.

For the purpose of holding the latch 30, and, consequently, the needle bar 13, stationary, I provide a pawl 32, which is pivoted to the head, as shown at 33, the head

being cut away as shown at 34 to provide a recess between it and the face plate 17 in which the pawl can swing. This pawl is notched as shown at 35 to receive the lug 36, which extends outwardly from the upper end of the latch 30, and a spring 37, one end of which is attached to the pawl and the other end of which is attached to a pin 38 projecting inwardly from the face plate 17, tends to hold the pawl in locking engagement with the lug 36. The lower end 39 of the pawl is cammed, so that if the latch 30 is moved toward the pawl 32 during the upward stroke of the needle bar 13, no harm will result, but the pawl 32 will be rotated against the tension of the spring 37 so as to permit the lug 36 to be received by the notch 35.

The lug 36 is provided with an opening 40 for receiving the rod 41, the lower end of which is pivoted at 42 upon the face plate 17. This rod is, therefore, free to move in a plane parallel to the plane in which the latch 30 moves, and by moving the rod 41 to the left (Figures 4, 5 and 6), the lug 36 can be brought into position to be received by the notch 35 in the pawl 32, or by moving the latch 30 to the right, it can be brought into engagement with the pin 29. For moving the rod 41 to either of its extreme positions, I mount a bell crank lever 43 upon a bracket 44 secured to one side of the head and connect one arm of this bell crank lever with the rod 41 by means of a link 45 having an opening in its free end in which the rod 41 can freely move. The other arm of the bell crank lever is connected by means of a link 46 with a second bell crank lever 47 mounted upon the arm of the sewing machine, and this lever may in turn be connected by means of a link 48 with a suitable lever 49, which may be operated by the hand, the foot or the knee of the operator, a spring 50 being used to return the lever to a position corresponding to the position of the rod 41 which places the needle bar 13 in operation.

If desired, suitable adjustable stops 51 may be mounted upon the side of the arm 21 to limit the movement of the bell crank lever 47.

To prevent the accidental detachment of the latch 30 from its pivot pin 15, and to guide it in its movements, I provide the link 19 with a lateral extension 52; which is turned back upon itself, as shown at 53, so as to provide a slot in which the latch 30 can move.

While I have described the details of construction of the preferred embodiment of my invention, it is to be clearly understood that my invention is not limited to these details of construction, but is capable of other adaptations and modifications within the scope of the appended claims.

Having thus described my invention, what I claim is:

1. A sewing machine comprising a head having aligned upper and lower bearings, said lower bearing being of larger diameter than said upper bearing, a hollow needle bar slidably mounted in said lower bearing, a second needle bar slidably mounted in said hollow needle bar and said upper bearing, a boss projecting from said second needle bar above the upper end of said hollow needle bar, a slotted link secured to said boss, a face plate having a slot parallel with the slot in said link, a pin projecting from the upper end of said hollow needle bar and through the slots in the said link and said face plate, a latch pivotally mounted on said pin, said latch comprising means for engaging said boss to lock said needle bars together, an apertured lug extending from said latch, a rod extending through the aperture in said lug, one end of said rod being pivotally mounted upon said face plate, a link having a bearing for the other end of said rod, a pawl for holding said latch in its release position, and means whereby said link can be actuated to engage said latch with, or release it from, said boss.

2. A sewing machine comprising a head having aligned upper and lower bearings, a hollow needle bar slidably mounted in said lower bearing, a second needle bar slidably mounted in said hollow needle bar and said upper bearing, a boss projecting from said second needle bar, a slotted link secured to said boss, a face plate having a slot parallel with the slot in said link, a pin projecting from the upper end of said hollow needle bar and through the slots in the said link and said face plate, a latch pivotally mounted on said pin, said latch comprising means for engaging said boss to lock said needle bars together, an apertured lug extending from said latch, a rod extending through the aperture in said lug, one end of said rod being pivotally mounted upon said face plate, a link having a bearing for the other end of said rod, a pawl for holding said latch in its release position, and means whereby said link can be actuated to engage said latch with, or release it from, said boss.

3. A sewing machine comprising a head having aligned upper and lower bearings, a hollow needle bar slidably mounted in said lower bearing, a second needle bar slidably mounted in said hollow needle bar and said upper bearing, a boss projecting from said second needle bar, a slotted link secured to said boss, a pin projecting from the upper end of said hollow needle bar and through the slot in the said link, a latch pivotally mounted on said pin, said latch comprising means for engaging said boss to lock said needle bars together, an apertured lug ex-

- tending from said latch, a rod extending through the aperture in said lug, one end of said rod being pivotally mounted, a link having a bearing for the other end of said rod, a pawl for holding said latch in its release position, and means whereby said link can be actuated to engage said latch with, or release it from, said boss.
4. A sewing machine comprising a head having aligned upper and lower bearings, a hollow needle bar slidably mounted in said lower bearing, a second needle bar slidably mounted in said hollow needle bar and said upper bearing, a boss projecting from said second needle bar, a slotted link secured to said boss, a pin projecting from the upper end of said hollow needle bar and through the slot in the said link, a latch pivotally mounted on said pin, said latch comprising means for engaging said boss to lock said needle bars together, a pawl for holding said latch in its release position, and means whereby said latch can be actuated to engage with or disengage said boss.
5. A sewing machine comprising a head having spaced bearings, a hollow needle bar slidably mounted in one of said bearings, a second needle bar slidably mounted in said hollow needle bar and the other of said bearings, a boss projecting from said second needle bar above the upper end of said hollow needle bar, a slotted link secured to said boss, a pin projecting from the upper end of said hollow needle bar and through the slot in said link, a latch pivotally mounted on said pin, said latch comprising means for engaging said boss to lock said needle bars together, and means whereby said latch can be engaged with and disengaged from said boss to permit said second needle bar to reciprocate relatively to said hollow needle bar.
6. A sewing machine comprising a head having spaced bearings, a hollow needle bar slidably mounted in one of said bearings, a second needle bar slidably mounted in said hollow needle bar and the other of said bearings, a boss projecting from said second needle bar, a slotted link secured to said boss, a pin projecting from said hollow needle bar and through the slot in said link, a latch pivotally mounted on said pin, said latch comprising means for engaging said boss to lock said needle bars together, and means whereby said latch can be engaged with and disengaged from said boss to permit said second needle bar to reciprocate relatively to said hollow needle bar.
7. A sewing machine comprising a head having spaced bearings, a hollow needle bar slidably mounted in one of said bearings, a second needle bar slidably mounted in said hollow needle bar and the other of said bearings, a boss projecting from one of said needle bars, a slotted link secured to said
- boss, a pin projecting from the other of said needle bars and through the slot in said link, a latch pivotally mounted on said pin, said latch comprising means for engaging said boss to lock said needle bars together, and means whereby said latch can be engaged with and disengaged from said boss to permit one of said needle bars to reciprocate relatively to the other.
8. A sewing machine mechanism, comprising a support, a plurality of needle bars slidably mounted in said support, a lever pivotally mounted on one of said needle bars, a shoulder on said lever, a shoulder on the other of said needle bars, and means on said support for selectively moving said first named shoulder into or out of the path of said second named shoulder to connect or disconnect said needle bars, respectively.
9. A sewing machine comprising a head having spaced bearings, a hollow needle bar slidably mounted in one of said bearings, a second needle bar slidably mounted in said hollow needle bar and the other of said bearings, and a pivotally swinging latch for connecting said needle bars together.
10. A sewing machine comprising a head, first and second cylindrical needle bars guided for reciprocation in said head, a latch member pivotally attached to the outside of said first needle bar adapted to engage said second needle bar, and means for moving said latch member into and out of latching position, said means remaining in operative engagement with said latching member throughout the full stroke reciprocation of said first needle bar.
11. A sewing machine comprising a pair of needle bars, means for reciprocating one of said needle bars, a latch member pivotally connected to one of said needle bars and moving therewith, a latch actuating member having a stationary pivotal mounting, and a lost motion connection between said latch member and said latch actuating member comprising an opening in one of said members and a portion of the other of said members engaging in said opening.
12. A sewing machine comprising a pair of needle bars, means for reciprocating one of said bars, a latch pivotally carried on one of the said bars, a pawl spaced from the normal path of movement of said latch, said latch having a lug adapted for engagement with said pawl, and means for shifting said latch to cause the path of movement of said lug to intersect the path of movement of said pawl.
13. A sewing machine comprising a head, a shaft guided in said head for reciprocation, said shaft being adapted to carry a needle, a sleeve surrounding said shaft and adapted for reciprocation thereon, said sleeve also being adapted to carry a needle, an operating crank in said head, a link connecting said

operating crank with said shaft for reciprocating the same, a slot in one wall of said head, and a guide member projecting from said sleeve for guidance in said slot.

14. A sewing machine comprising a head having an upper bearing and a lower bearing, a shaft having its upper end guided in said upper bearing, a sleeve surrounding said shaft and guided in said lower bearing, the upper end of said sleeve terminating intermediate said bearings, an operating crank in said head, means operatively connecting said crank with said shaft, and releasable latching means for operatively connecting said shaft and said sleeve.

15. A sewing machine comprising a pair of needle bars, means for reciprocating one of said needle bars, and means for releasably latching said needle bars together comprising a slotted link pivotally connected to one of said needle bars, and a lug projecting from the other of said needle bars and playing in said slot.

16. A sewing machine comprising a head, a pair of needle bars slidably mounted in said head, an operating crank having permanent operative connection with one of said needle bars for reciprocating the latter during all rotation of said crank, a latching member pivotally connected to one of said needle bars for reciprocation therewith, said latching member being pivoted on a substantially horizontal axis for swinging movement in a vertical plane, a shoulder on said latching member adapted to engage a shoulder on the other needle bar when said latching member has been swung to one position, a shoulder on said latching member adapted to engage another shoulder, stationary relative to the reciprocations of the needle-bars, for holding said first-mentioned needle bar in stationary position when said latching member has been swung to another position, and means for swinging said latching member between said two positions.

17. A sewing machine comprising a head, a pair of needle bars slidably mounted in said head, means for reciprocating one of said needle bars, a latching member pivotally connected to one of said needle bars for reciprocation therewith, said latching member being pivoted on a substantially horizontal axis for swinging movement in a vertical plane, a shoulder on said latching member adapted to engage a shoulder on said other needle bar when said latching member has been swung to one position, a shoulder on said latching member adapted to engage another shoulder, stationary relative to the reciprocations of the needle-bars, for holding said first mentioned needle bar in stationary position when said latching member has been swung to another position, and actuating means remaining in operative engagement with said latching member throughout the full stroke reciprocation of its associated needle bar for swinging said latching member between said two positions.

18. A sewing machine comprising a head, a hollow needle bar, a second needle bar slidably mounted in said hollow needle bar, a latching member pivotally connected to one of said needle bars for reciprocation therewith, said latching member having swinging movement in a substantially vertical plane, a shoulder on said latching member adapted to engage a shoulder on the other needle bar when said latching member has been swung to open position, a shoulder on said latching member adapted to engage another shoulder, stationary relative to the reciprocations of the needle bars, for holding its associated needle bars in stationary position when said latching member has been swung to another position, and means for swinging said latching member between said two positions.

In witness whereof, I hereunto subscribe my name this 1st day of December, 1922.

OTTO P. WATSON.
